RECTIFIER SYSTEM

Frederick E. Terman, Stanford University, Calif.,
assignor to Wired Radio, Inc., New York, N. Y.,
a corporation of Delaware

Application December 23, 1929
Serial No. 416,173

9 Claims. (Cl. 250—27)

My invention relates broadly to electron tube rectifiers and more particularly to an inverted electron tube circuit arranged to operate as a rectifier.

5 One of the objects of my invention is to provide an improved rectifier circuit having a step-down voltage characteristic whereby relatively large potentials of alternating characteristic may be impressed across the rectifier circuit for 10 deriving a rectified current of relatively small amplitude.

Another object of my invention is to provide a rectifier or detector circuit which may be subjected to relatively large potentials for obtaining 15 stabilized rectifier or detector operation without reaction due to the relatively large impressed potential.

A further object of my invention is to provide a system of rectification wherein the energy 20 to be rectified is impressed across the plate and cathode electrode of a three element tube and the rectified energy derived in an output circuit connected to the grid and cathode electrodes of the electron tube system.

25 Other and further objects of my invention reside in the circuit arrangement for an electron tube rectifier set forth more fully in the specification hereinafter following by reference to the accompanying drawing, wherein:

30 Figure 1 illustrates one form of rectifier system embodying the principles of my invention; and Fig. 2 illustrates a modified circuit arrangement for the rectifier system of my invention.

In the circuits of my invention I employ the 35 principle of the inverted electron tube as set forth more fully in my copending application Serial No. 405,363, filed November 7, 1929, now Patent No. 1,846,043, issued February 23, 1932, and entitled "Electron tube circuit". The input 40 system for the electron tube employed in my invention connects between the plate and cathode electrodes while the output system in the electron tube of my invention connects between the grid and cathode electrodes. The plate electrode 45 may be normally maintained at negative potential while the grid electrode is normally maintained at positive potential. It is also possible to operate the system of my invention without applying a direct current biasing voltage to the plate since the characteristic curve of an inverted three electrode tube showing grid current plotted against plate voltage shows a very sharp peak at the point of zero plate voltage. Conditions should be so maintained that substantially no plate current will flow; the tube

structure is one important controlling condition in this respect, and such operation is facilitated if the incoming signal is weak. The operation will be better understood by reference to Fig. 6 of my Patent No. 1,846,043, which shows a complete static characteristic curve of grid current plotted against plate voltage. The energy to be rectified is impressed across the plate and cathode electrodes while the rectified energy is derived in the circuit connecting the grid and cathode electrodes. The step-down voltage ratio obtainable in the electron tube system is dependent upon the structure and design of the electron tube employed. In my copending application Serial No. 413,555, filed December 12, 1929, entitled Electron tube, I have illustrated certain constructions of electron tubes which may be employed in the circuit arrangement of my invention to secure the desired voltage transmission.

In Fig. 1, I have illustrated a modified form of circuit arrangement embodying my invention wherein a high resistance leak path is provided in series with the plate electrode of the electron tube system which includes electron tube 1 having cathode 2, grid electrode 3 and plate electrode 4. The cathode is heated from battery system 5. The output circuit includes battery 6 having one terminal thereof directed toward the grid electrode 3 in such manner that through the output load a positive bias is maintained on the grid 3. In series with the plate circuit there is disposed a condenser 7 shunted by the high resistance leak path 8 by which the energy to be rectified is supplied to the plate electrode 4 and in circuit with cathode 2. The input current flowing in the plate circuit must pass through this condenser unit and produces a direct current voltage drop between cathode and plate which is effective in varying the electric field between cathode and grid, and hence varies the output current delivered by the grid. The energy to be rectified is supplied across the leads designated at 9. The rectified energy is delivered across the leads designated at 10. Rectification may be said to occur in the plate circuit or input circuit. The rectification occurs because the characteristic curve of plate current against plate voltage is not linear. Since grid 3 is maintained at a potential positive with reference to cathode 2, a direct current will flow from cathode 2 through source 6, through load 10, and to grid 3. The electron flow between cathode and grid will be varied by the variations in the electric field between

cathode and grid caused by the variations in the input potential impressed between plate and cathode. The current flowing to the positive grid depends upon the electric field existing between cathode and grid, and is substantially independent of how this field is produced. Both the grid and plate potentials affect the magnitude of this field.

In Fig. 2 I have shown an arrangement of 10 rectifier circuit in which the input system includes biasing battery 12 for normally maintaining the plate 4 at negative potential. Relatively high potentials impressed across the circuit 9 are rectified and produce relatively low 15 rectified current at the terminals 10 for distribution to the load.

No current flows in the plate circuit because the plate is negatively biased. This bias should be adjusted to the portion of the characteristic curve of suitable curvature. The alternating voltage impressed between plate and cathode will vary the electric field between plate and cathode, including the electric field between grid and cathode, and hence will vary the output 25 current delivered by the grid. I have usually found greater sensitivity by employing the condenser and leak in the plate circuit with little or no plate bias. The higher the resistance of the plate leak, the more sensitive the detection.

30 In both forms of the circuits as described, the direct current output derives its essential energy from the grid battery 6. The direct current flowing in the grid circuit is, however, varied or controlled in accordance with the alternating voltage impressed between plate and cathode. The type of rectification obtained by the arrangements shown in Figs. 1 and 2 is analogous to the rectification obtained in the normal type 35 of detector circuit with the usual three electrode tube applying the input to the grid and delivering output from the plate.

Fig. 1 corresponds to the ordinary type of 40 grid-leak grid-condenser detection with normally operated tube in which the applied signal voltage is rectified by the non-linearity of the grid-filament circuit, producing a rectified grid current that must flow through the grid-leak 45 grid-condenser impedance and produce a voltage drop, which in turn affects the plate current of the tube by ordinary amplifier action, as described in my paper which appeared in the 50 October 1928 issue of the Proceedings of the Institute of Radio Engineers, vol. 16, page 1384.

Fig. 2 corresponds to the usual type of detector 55 circuit with normally operated tube employing a negatively biased grid battery wherein rectification may be said to occur in the output or plate circuit. In the system of my invention, particular methods are employed for applying the inverted electron tube to detector circuits heretofore known with normally operated tubes having input connected to the grid and output connected to the plate. It should be particularly noted that in the system of my invention, no substantial portion of the output energy is derived from the alternating current input but that substantially all of the output energy is derived from the grid battery 6. In the inverted vacuum tube system of my invention, an alternating current applied to the plate has the same effect on the output or grid current as though a potential of similar wave form but much less voltage had instead been added to the grid battery in the output circuit. In the system

shown in Fig. 2, rectification takes place in the output or grid circuit.

In leak condenser rectification, as shown in Fig. 1, the rectification results from the non-linear relation that exists between the plate current and the plate voltage when the plate potential is at or near zero volts with respect to the cathode. With detection of this type, the relationship between positive grid voltage and grid current is preferably linear. Leak condenser rectification always takes place with a grid current which increases as the voltage being rectified becomes greater. In contrast with this anode current rectification with the inverted tube makes use of the non-linear relation that exists between anode current and anode voltage when the plate is biased with a relatively high negative potential that approaches the cut-off condition. Anode rectification of this type takes place entirely in the anode circuit and is not accompanied by the presence of grid current unless the rectifier is overloaded. Anode rectification can only take place when the operating conditions are such that the anode current and anode voltage have a non-linear relation.

100 While I have described the rectifier and detector circuits of my invention in certain preferred embodiments, I desire that it be understood that modifications may be made and that no limitations upon my invention are intended other than are imposed by the scope of the appended claims.

What I claim as new and desire to secure by Letters Patent of the United States is as follows:

1. In a rectifier circuit an electron tube including cathode, grid and plate electrodes, an input circuit connected across said plate and cathode electrodes, an output circuit connected across said grid and cathode electrodes, a source of energy connected for applying a positive potential to said grid with respect to said cathode, and means connected in circuit with said plate electrode for determining the operation of said electron tube as a rectifier whereby potentials supplied across said plate and cathode electrodes are rectified and delivered at lower amplitude to the output circuit.

110 2. In a rectifier system, an electron tube having cathode, grid and plate electrodes, an input circuit interconnecting said plate and cathode electrodes, an output circuit interconnecting said grid and cathode electrodes, a condenser shunted by a resistance element disposed in series with said plate electrode in said input circuit, means for charging said grid electrode at positive potential whereby relatively high potentials impressed across said input circuit are stepped down, rectified, and the rectified current delivered at lower amplitude to said output circuit.

120 130 3. A rectifier system comprising an electron tube including cathode, grid and plate electrodes, an input circuit interconnecting said plate and cathode electrodes, an output circuit interconnecting said grid and cathode electrodes, means for maintaining said grid electrode at positive potential, and a reactance connected in circuit with said plate electrode in said input circuit whereby relatively high potentials impressed across said input circuit are stepped down, rectified and the rectified current of relatively low amplitude delivered to said output circuit.

135 140 4. In an inverted electron tube rectifier system, an electron tube having at least one cathode, one grid, and one plate, a source of alternating cur-

- rent to be rectified connected to said plate and said cathode, a source of direct current grid potential, and an output circuit connected through said source of grid potential to said grid and said cathode for applying to said grid a potential positive with reference to said cathode. 5 and said cathode, a source of direct current potential connected in series between said source of alternating current and said plate and cathode for applying to said plate a potential negative with respect to said cathode, a source of direct current grid potential, and an output circuit connected through said source of grid potential to said grid and said cathode for applying to said grid a potential positive with reference to said cathode. 60
5. In an inverted electron tube rectifier system, an electron tube having at least one cathode, one grid, and one plate, a source of alternating current to be rectified connected to said plate and said cathode, means connected in series between said source and said plate and cathode for maintaining said plate at a determined potential with reference to said cathode, a source of direct current grid potential, and an output circuit connected through said source of grid potential to said grid and said cathode for applying to said grid a potential positive with reference to said cathode. 85
- 10 6. In an inverted electron tube rectifier system, an electron tube having at least one cathode, one grid, and one plate, a source of alternating current to be rectified connected to said plate and said cathode, a condenser connected in series between said source and said plate and cathode, a high resistance connected in shunt with said condenser, a source of direct current grid potential, and an output circuit connected through said source of grid potential to said grid and said cathode for applying to said grid a potential positive with reference to said cathode. 90
- 15 7. In an inverted electron tube rectifier system, an electron tube having at least one cathode, one grid, and one plate, a source of alternating current to be rectified connected to said plate and said cathode, a condenser connected in series between said source and said plate and cathode, a high resistance connected in shunt with said condenser, a source of direct current grid potential, and an output circuit connected through said source of grid potential to said grid and said cathode for applying to said grid a potential positive with reference to said cathode. 95
- 20 8. In a rectifier system employing a three electrode electron tube, the method of rectification which consists in applying the voltage to be rectified between the plate and cathode of said tube, maintaining said plate at a negative potential with reference to said cathode, maintaining said grid at a positive potential with reference to said cathode, and delivering the output of said system from said grid and said cathode. 100
- 25 9. In a device of the class described, an electron tube having at least three electrodes, namely a plate, a cathode and a grid, an input circuit conductive of alternating potentials and connected between said plate and said cathode, an output circuit including a source of energy for positively biasing said grid with respect to said cathode and connected between the two electrodes last mentioned, and means including the structural arrangement of said electrodes and the provision of a zero-bias applied to said plate 105 with respect to said cathode for causing said alternating potentials to produce a rectifying control of the currents in said output circuit. 105
